CLAIM

The ornamental design for a refrigerant compressor for a vehicle air conditioner, as shown.

DESCRIPTION

FIG. 1 is a left side view of the refrigerant compressor, according to our design.

FIG. 2 is a right side view of the refrigerant compressor, according to our design.

FIG. 3 is a cross-sectional view of the refrigerant compressor along line 3—3 of FIG. 1, showing the shape of our design.

FIG. 4 is a rear perspective view of the refrigerant compressor, according to our design; and,

FIG. 5 is a cut-away view of the refrigerant compressor of FIG. 4, showing the shape of our design.

The broken line portions of FIGS. 1—5 are for illustrative purposes only and form no part of the claimed design.
